UNITED STATES PATENT OFFICE.

FRANCIS A. WAGNER AND FOREST H. HARTZELL, OF DAYTON, OHIO, ASSIGNEES TO
THE AMERICAN MECHANICAL TOY COMPANY, OF DAYTON, OHIO, A CORPORATION
OF OHIO.

SWITCH.

1,361,937.

Specification of Letters Patent. Patented Dec. 14, 1920.

Application filed March 20, 1916. Serial No. 85,261.

To all whom it may concern:

Be it known that we, FRANCIS A. WAGNER and FOREST H. HARTZELL, citizens of the United States, residing at Dayton, in the county of Montgomery and State of Ohio, have invented certain new and useful Improvements in Switches, of which the following is a specification, reference being had therein to the accompanying drawing.

This invention relates to switches. It is an object of the invention to provide a multiple position switch which is operated by continuous movement of the switch arm in one direction. It is a further object of the invention to utilize this switch in connection with a motor so that when the switch arm is at either extreme of its movement the motor will rotate in the same direction. As the arm moves from one extreme to the other in the first intermediate position the current will be cut off, in the second intermediate position the motor will rotate in a reverse direction and in the third intermediate position the current will again be cut off. Another object of the invention is to so combine the switch with a motor and its bed plate that the wiring may be of a minimum amount and of the greatest simplicity, the parts being thoroughly insulated, neatly arranged, compact and simple.

In the accompanying drawings, Figure 1 is a plan view of the combined switch and motor, parts being broken away for the sake of clearness; Fig. 2 is a plan view of the switch with the cap removed; Fig. 3 is a sectional view through the switch on the line 3-3 of Fig. 1, looking in the direction of the arrows; Fig. 4 is a detail inverted view of the movable contact member; Fig. 5 is a diagrammatic view showing the circuit with the movable contact member in a position to cause the motor to rotate in one direction; Fig. 6 is an auxiliary diagrammatic view showing the position that the movable contact member occupies relatively to the position shown in Fig. 5 when the circuit is open; and Fig. 7 is an auxiliary diagrammatic view showing the position that the movable contact member occupies relatively to the position shown in Fig. 5 when the motor is rotating in a direction opposite to that in which it rotates when the movable contact member is in the position shown in Fig. 5.

In the particular embodiment of the in-

vention here shown we have provided a motor base 1 upon which is mounted a suitable motor 2 provided with the usual armature and field circuit. The forward portion of the base is provided with a circular opening 3 and with lugs 4 projecting into the said opening. A plate 5 comprising any suitable insulating material, such as fiber, is mounted above the opening 3 and attached to the lugs 4 in any suitable manner. Fixed to the plate 5 are a plurality of separated metallic contact members 6, 7, 8 and 9. As here shown, the members are arranged circumferentially around the plate 5 and are elongated. The members 6 and 9 constitute one diagonal pair and the members 7 and 8 constitute another diagonal pair. Each member is fastened to the base at one end by means of a screw 10 which also constitutes a binding post. The plate 5 is provided with an opening 11 into which the opposite ends of the contact members are bent, as shown at 12, thereby insuring a very durable structure. A pair of binding posts 13 and 14 is also provided and mounted upon the motor base 1 adjacent the switch. Conductors 15 and 16 are connected to the respective binding posts. The conductors are in communication with any suitable source of power, such as a battery illustrated diagrammatically in Fig. 5 at 17. A conductor 18 is attached at one end to the lower end of the binding post 13, extends along the bottom of the base 1, is passed through an opening 19 in the plate 5 and is attached to the contact member 9 by means of its fastening screw 10. In this connection it may be stated that the plate 5 is provided with a plurality of such openings 19, there being an opening adjacent each of the contact members, through which the several conductors may pass and be attached to their contact members. Attached at one end to the lower portion of the binding post 14 is a conductor 20 which is connected to the armature coils, indicated generally and diagrammatically in Fig. 5 at 21, at its opposite end. The circuit through the armature is completed by a conductor 22 which connects the same with the contact member 6, the conductor passing through one of the openings 19 above mentioned. At 23 in Fig. 5 we have shown diagrammatically the field coils of the motor. Conductors 24 and 25, respectively, connect these field coils with 105

110

the contact members 7 and 8, respectively. The conductors 24 and 25 are also located below the base plate of the motor and extend through openings 19 in the manner 5 above described. The plate 5 is also provided with a central vertically extending stud 26 of wood or some other suitable insulating material. The stud is located centrally between the contact members. A 10 member 27 of insulating material provided with an opening 27' is rotatably mounted upon the stud 26. This member is provided upon its lower surface with a pair of elongated spaced-apart parallel strips 28 and 29, 15 of metal or some other suitable conducting material. These strips are attached to the member 27 by providing openings 30 in the member into which the ends of the respective contact members 28 and 29 are 20 bent, as shown at 31. The member 27 is rotated by means of a switch arm 32 which is attached to the same in the following manner. The switch arm is provided with a central opening 32' adapted to receive the 25 stud 26. The member 27 is provided at one end thereof and centrally between the elongated contact members 28 and 29 with an opening 33 into which the bent down end 34 of the arm 32 projects. The switch arm 30 32 is held in place against the member 27 by means of a coiled spring 35 encircling the stud 26 and held in place by means of an abutment or a washer 36, at the upper end of the stud and fastened thereto by means 35 of a wooden screw 37. We have also provided a casing 38 to inclose the switch and the contact members and this casing is provided with a circumferential slot 39 through which the switch arm 32 projects. 40 The ends of the slot 39 constitute stops 40 and 41 to limit the movement of the switch arm at the two extremes.

The operation of our switch is substantially as follows: Assuming that the parts 45 are in the position shown in Fig. 5 the current will pass in the direction of the arrows through the conductors 16 and 20, through the armature 21, through the conductor 22 to the contact member 6, across the contact 50 member 28 to the contact member 7, then through the field coils in the direction of the arrow to the contact member 8, across the contact member 29 to the contact member 9 and then back to the battery. It will 55 be assumed for convenience sake that when the current is passing through the circuit, as shown, in the direction of the arrows, the motor is rotating clockwise. It will be seen that when the motor is so rotating the switch 60 arm will be against the stop 40, as shown in Fig. 1, and the contact members 28 and 29 extend vertically. Then, assuming that the switch arm is moved clockwise it will be seen that the contact members 28 and 29 will 65 assume a diagonal position, as shown in Fig.

6. When in this position the circuit is open and no current is flowing through the motor and the same will stop. As the arm is moved to the next position the members 28 and 29 will assume a horizontal position 70 and span the members 6 and 8 and 7 and 9, respectively, as shown in Fig. 7. When the parts are in the last described position it will be obvious that the flow of current through the field coils is reversed. This reversal of the flow of current through the field coils will also reverse the direction of rotation of the motor and cause the same to rotate counterclockwise. As the movement of the switch arm is continued the members 75 28 and 29 will again assume a diagonal position, whereby the circuit will again be opened and the motor will stop. As the movement of the switch arm is still further continued it will finally engage the stop 41 80 and when so engaged the members 28 and 29 will again assume a vertical position, as shown in Fig. 5, and the current will so flow through the field coils as to cause the motor to again rotate in a clockwise direction. 85 90

It will be seen that we have provided a five position switch. In two positions the motor will rotate clockwise, in two other positions the circuit will be broken and in the central position the motor will rotate counterclockwise. When the switch arm is 95 against either of the stops 40 or 41 the motor is rotating clockwise, when the switch arm is in the second position the motor is not running, when in the third position it is reversed and when in the fourth position it is again stopped. It is to be understood that it is immaterial, however, whether the motor rotates clockwise or counterclockwise, the specification of the direction of rotation being merely for the sake of convenience and in a like manner it is immaterial whether the parallel contact members 28 and 29 are 100 in vertical or horizontal or any other position as far as the operation of the device is concerned, the particular position being specified merely to more clearly bring out the operation thereof.

It will be seen that the several changes are performed by a continuous movement of 115 the operating arm in one direction.

We have also provided a very compact and simple structure in which the conducting wires are all unexposed and very short. The switch arm and movable member 27 are 120 easily replaceable and are characterized by great simplicity, the arm being held tightly in engagement with the member 27 by means of the spring 35. The parts are also preferably insulated. The switch can be 125 utilized not only in connection with large motors but is also especially adapted for use in connection with small or toy motors. The particular switch here shown is also applicable for use wherever a reversal of the di- 130

rection of flow of the current is desired, whether in connection with a motor or elsewhere. For instance, we have here shown the circuit in which the current is reversed 5 as comprising the circuit of a field coil, yet it will be obvious that the reversal of the motor would take place in the same manner if the current through the armature were reversed instead.

10 Having thus fully described our invention, what we claim as new and desire to secure by Letters Patent, is:—

15 1. In a switch, the combination, with a plate of insulating material and pairs of contact members arranged on said plate, the members of each pair being electrically connected, a plate having oppositely positioned contacting strips to connect the opposite members of said contacts, a stud secured in 20 the plate of insulating material, a spring on the stud forcing said plates toward each other, a housing for said mechanism, having a slot and a handle secured to said second plate and movable in said slot to open and 25 close the electric circuit.

2. In a switch, a plate of insulating ma-

terial having an opening, a contact member mounted on said plate, one end of said contact member extending into said opening, and a combined binding post and clamping 30 device at the other end of said contact member, said plate of insulating material being provided with an opening adjacent said combined binding post and clamping device through which the conductor is led to 35 the binding post.

3. The combination, with a motor base having an opening, of a plate of insulating material mounted above said opening, contact members mounted on said plate, a 40 pair of binding posts mounted upon said motor base adjacent said plate, openings in said plate adjacent said contact members, and conductors connected at one end to said contact members passing through said openings and connected to said binding posts and 45 motor circuits.

In testimony whereof we affix our signatures.

FRANCIS A. WAGNER.
FOREST H. HARTZELL.
